RAY P. JACKSON, OF EDGEWOOD, PENNSYLVANIA, ASSIGNEE TO WESTINGHOUSE ELECTRIC AND MANUFACTURING COMPANY, A CORPORATION OF PENNSYLVANIA.

IRON-PORCELAIN INSULATING-SUPPORT.

1,199,466.

Specification of Letters Patent. Patented Sept. 26, 1916.

Application filed February 19, 1914. Serial No. 819,823.

To all whom it may concern:

Be it known that I, RAY P. JACKSON, a citizen of the United States, and a resident of Edgewood, in the county of Allegheny and State of Pennsylvania, have invented a new and useful Improvement in Iron-Porcelain Insulating-Supports, of which the following is a specification.

My invention relates to electrical insulating bodies or structures and particularly to such bodies or structures as are employed for supporting high-voltage lines, conductors or devices, and it has special reference to insulating supports which are adapted for outdoor installation and exposure to severe mechanical and electrical service conditions.

Heretofore, insulating supports have usually been made of porcelain having corrugated surfaces or other structural characteristics to provide very long leakage paths between the conductors or devices and the ground in order to avoid surface discharges. Because such porcelain supports were exposed, they were of a cumbersome construction to provide sufficient strength to resist the mechanical strains imposed upon them. By means of my invention, an insulating support is provided which possesses qualities adapting it particularly for use in places where mechanical strength is a requisite.

Furthermore, my insulating support may be utilized to insulate very high-voltage conductors and, at the same time, be materially reduced in size and simplified in construction.

As disclosed in patent application Serial No. 558,744, assigned to the Westinghouse Electric and Manufacturing Company, it is highly desirable to shape the insulating body of a conductor support to conform to the normal lines of force which represent the existing electrostatic field between the conductor and the ground. By reason of this special surface configuration, the insulating body is capable of withstanding the full voltage which the same path through air would withstand if the insulating body were absent. Since the air is thus utilized to its full value as an insulator, the insulating body may be materially reduced in size. Of course, it is only necessary to have the insulating surface of my support conform approximately to the electrostatic flow lines and, therefore, if so desired, for uniformity of parts, the insulating surface may intercept some of these flow lines.

Another advantage accruing from the use of my invention is that the insulating surfaces are protected from deposits of dust and other extraneous matter which tend to lower the resistance of the leakage paths to the ground.

My invention is illustrated in the single figure of the accompanying drawing which is a view, partially in elevation and partially in section, of an insulating support constructed in accordance therewith.

An upper and outer member 1, preferably made of metal, such as cast iron, and having a downwardly and outwardly flared portion or petticoat 2, is provided with a top extension 3 having screw holes 4 therein, by means of which a clamp or other retaining means (not shown) for a high voltage conductor or line, may be secured. Disposed within and beneath the member 1, and insulated therefrom by a porcelain element 5, is a second member 6 that is provided with a corresponding petticoat 7 and an elongated upwardly extending portion 8. The porcelain element 5 extends upwardly into the upper portion of the member 1, and is provided with recesses 9 formed in the inner and outer surfaces of its upper and lower portions, substantially as shown. The upper portion 8 of the member 6 projects into the interior of upper portion of the porcelain element 5. Cement or binding material 10 is interposed between the element 5 and the two conducting members 1 and 6 in order to hold them in fixed relation, and to insure rigidity to the insulating support. Interposed between the petticoat 2 and the petticoat 7 is a body 11 of material having high dielectric properties and molded to provide a leakage surface which conforms to the direction of the electrostatic flow lines between the conducting members 1 and 6. To preclude the deterioration of the molded material 11 and to provide a high-resistance leakage path, an annular porcelain member 12 of inverted frusto-conical shape, is placed intermediate the petticoats 2 and 7. The member 12 is shaped to coincide substantially with the electrostatic flow lines, as above mentioned.

It will be understood that this requirement is not essential and, for low voltages, not necessary, but, in a high-voltage installation, it is desirable to provide the member 12 with surfaces which will conform substantially to the electric lines of force established between the conducting members 1 and 6.

At present, it is impossible to manufacture a suitable molding material 11 which will not deteriorate when exposed to severe weather conditions. In time, the exposed surfaces of these molding materials become honeycombed and filled with particles of dust and other matter which decrease the insulating properties thereof. As a result, the resistance of the leakage path between the petticoats 2 and 7 will be decreased unless the porcelain member 12, or other suitable means, is utilized to protect the exposed surface of the molded material 11. Again, porcelain material may be readily molded into various shapes before being glazed. This particularly adapts porcelain for use where the exposed insulating surface must conform to the electrostatic flow lines, as mentioned above.

From the drawing, it will be seen that a plurality of conducting members 6, one insulated from the other by means of the nested insulating elements 5, are provided for each support, the total number of conducting members depending upon the service conditions to which the insulating support will be subjected. Spaces 13 are left unoccupied by so positioning barriers 14 as to preclude the flowing of cement 10 or molded material 11 therein. This does not effect the insulating properties of my device and considerably lightens the assembled structure.

Inasmuch as the conducting members 1 and 6 are adequately insulated from one another, and the member 12 is interposed therebetween to provide a permanent leakage path of high resistance, the insulating structure is able to withstand such stresses as may be imposed thereupon by service conditions. The insulating elements 5 are interposed between the members 1 and 6, and are exposed only to compressive stresses which porcelain is particularly adapted to withstand.

The petticoats 2 and 7 shield the surfaces of the member 12 from rain and other matter which would lessen the resistance of the leakage path provided thereby, and, at the same time, also protect said member from mechanical blows or impacts which might result from the dropping of tools upon the

support or the falling of masses of sleet and ice from the conductor which is secured to the extension 3.

My invention is, of course, not restricted to any particular application, and I desire that its scope shall be limited only by the appended claims.

I claim as my invention:

1. An insulating support comprising a plurality of superposed and spaced conducting members nested one within another, said conducting members provided with elongated upper portions and conically flared lower portions, insulating members interposed between adjacent conducting members to resist compressive stresses, and porcelain members bridging the spaces between adjacent flared portions of the conducting members in order to provide leakage paths of permanently high resistance. 80

2. An insulating support comprising a plurality of superposed and spaced conducting members nested one within another, insulating members interposed between adjacent conducting members in order to resist 85 electrical and mechanical stresses existing therebetween, and porcelain members disposed in the leakage paths between said adjacent conducting members.

3. An insulating support comprising a 90 plurality of superposed and spaced conducting members provided with conically flared lower portions, means for insulating adjacent conducting members from each other, and porcelain conducting rings bridging the 95 spaces between the flared portions of said conducting members, the surfaces of said rings being shaped to substantially conform to the lines of force representing the electric field between said conducting members. 100

4. An insulating support comprising a plurality of superposed and spaced conducting members provided with elongated indentations and laterally flared portions, said indentations being nested one within 105 another, insulating members interposed therebetween to resist compressive stresses, and an insulating material molded between adjacent flared portions to substantially conform to the lines of force representing 110 the electric field between said conducting members.

In testimony whereof, I have hereunto subscribed my name this 16th day of Feb., 1914.

RAY P. JACKSON.
